CLAIM

We claim the ornamental design for a handheld portable computing device, substantially as shown and described.

DESCRIPTION

FIG. 1 is a perspective view of a handheld portable computing device in accordance with the present design. The handheld portable computing device can, for example, be a media player, media storage device, cellular phone and/or the like.

FIG. 2 is a front view for the media device shown in FIG. 1.

FIG. 3 is a rear view for the media device shown in FIG. 1.

FIG. 4 is a top view for the media device shown in FIG. 1.

FIG. 5 is a bottom view for the media device shown in FIG. 1.

FIG. 6 is a right side view for the media device shown in FIG. 1; and,

FIG. 7 is a left side view for the media device shown in FIG. 1.

The user interface typically includes a display and an input means such as a navigation mechanism and selection mechanism. The display is shown in broken lines.
